United States Patent Office.

HENRY SAUNDERS AND JAMES M. SAUNDERS, OF OXFORD, OHIO.

Letters Patent No. 69,369, dated October 1, 1867.

IMPROVEMENT IN HITCHING DEVICE FOR WHIFFLE-TREES.

The Schedule referred to in these Letters Patent and making part of the same

TO ALL WHOM IT MAY CONCERN:

Be it known that we, HENRY SAUNDERS and JAMES M. SAUNDERS, of Oxford, in the county of Butler, and State of Ohio, have invented certain new and useful improvements in Safety Hitching Devices for Whiffle-Trees; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists of a new and improved safety device for whiffle-trees, by which runaway, or unruly, or vicious horses may be promptly released from the carriage or other vehicle to which they are hitched, and thus save both the carriage and its occupants from injury or accident. In the drawings—

Figure 1 is a top plan view of the whiffle-tree with our devices attached, and also a sectional view of a portion.

Figure 2 is an edge view of the rear side of the whiffle-tree with our devices attached, and

Figure 3 is a plan view of ring sliding on the shaft or thill.

In constructing our device we attach to single-trees A, of any size used, arms B, made of metal, and bent and formed as shown in figs. 1 and 2, so as to leave a sufficient space between their curved ends and the ends of the single-tree for the easy movement of the end of a trace, and also so as to serve as stops for the bolts C C. We then fasten upon the single-tree, parallel with its length, and near either end, hollow tubes D, provided with a bolt, C, having about it a spiral spring, a, arranged so as to force out the bolt C against the arm or stop B and hold it there, as shown in the sectional view of fig. 1. The bolt C we make of sufficient length to project beyond the end b of the tube D, and to the end of the bolt we fasten a cord, c, and pass it over the pulleys d. As the arrangement is the same on either side of the centre of each single-tree, the cords c will come together and unite at e, as shown in fig. 1, and then pass united into the carriage. The breeching-strap of the harness we fasten to a loop, f, of the metal ring g, which slides on the shaft, which has a check, h, to limit its backward movement, and also for it to bear against when backing. In order that these rings may slide off the shaft easily, when attached to and are pulled by the breeching-strap, we make it in form as shown in fig. 3, and fasten the strap to the projecting loop.

In using our device with single or one-horse vehicle we pass the rings over the shafts and then slip the ends of the traces over the ends of the bolt C. Now, should the horse become unmanageable, it will be only necessary to pull upon the cords c to release him, for, as the cords c are pulled, the bolts C are drawn back, the ends of the traces drop, and as the horse moves forward the rings g slide from the shaft and the horse is free. The same arrangement may be used when two single-trees are connected to a whiffle-tree, and when two horses are hitched up instead of one. In that case each single-tree will be provided with the device, and the cords will come together, so that all the traces may be released at once.

Having thus described our invention, what we claim is—

The application to the whiffle-tree A of the arms or stops B, the cases D with the spring-bolt C encased therein, with the cords c and pulleys d, when the same are arranged to operate as herein shown and described.

HENRY SAUNDERS.

J. M. SAUNDERS.
